TOY JUMPING HORSE

Carl G. Gaustad, 908 Public Service Bldg.,
Portland, Oreg.

Filed Oct. 12, 1962, Ser. No. 72,089

Term of patent 14 years

(Cl. D34—5)

Fig. 1

Fig. 2

Fig. 3

Fig. 4

Fig. 5

FIG. 1 is a perspective view of a toy jumping horse showing my new design;

FIG. 2 is a top plan view;

FIG. 3 is a side elevational view;

FIG. 4 is a front elevational view; and

FIG. 5 is a rear elevational view with the spring plate removed and the seat in an extended position.

I claim:

The ornamental design for a toy jumping horse, as shown and described.
